UNITED STATES PATENT OFFICE.

MEYER SOYBEL, OF BROOKLYN, NEW YORK, ASSIGNOR, BY MESNE ASSIGNMENTS, TO INTERNATIONAL FOLDING PAPER BOX CO., INC., OF NORTH BERGEN, NEW JERSEY, A CORPORATION OF NEW JERSEY.

SUPPORTING DEVICE.

Application filed July 3, 1926. Serial No. 120,413.

My invention relates to supporting devices and refers particularly to devices of this character capable of being formed from a single blank and adapted to support commodities of an elongated form.

The object of my invention is a supporting device for certain classes of commodities, especially those having elongated members such as sticks, and which is capable of being formed from a single blank requiring only one glued portion, thus allowing economy in production advantageous packing facilities and ease of formation into the finished device.

Another object of my invention is a device of the character described in which the commodity is supported by two members, both of which are spaced from the surface upon which the device rests, thus allowing of a firm support for the commodity.

The above, and other advantageous properties of my device will be evident upon a consideration of this specification and the accompanying drawings.

In the accompanying drawings illustrating one form of the device of my invention, similar parts are designated by similar numerals.

Figure 1 is a perspective view of one form of the device of my invention.

Figure 2 is a cross-section through the line 2—2 of Figure 1.

Figure 3 is the blank employed in the production of the device shown in Figure 1.

The particular form of the device of my invention shown in the accompanying drawings is illustrated in the blank form in Figure 3 which comprises the top 10, 11, the bottom 12, 13 and the side 14 scored at the lines A—A, B—B, C—C and D—D. There is a plurality of holes 14, 14, 14 along the score line A—A.

The top member 10 is extended into the end flap 15 having the angular slot 16 and into the end flap 17 having the angular slot 18, and has the score lines A—E and A—F.

The top member 11 is extended into the end flap 19 having the hook catch 20 and

into the end flap 21 having the hook catch 22. There is a plurality of holes 23, 23, 23 along the line C—C, in alignment with the holes 14, 14, 14 when the device is in folded position.

The blank is folded along the score lines into the position shown in Figure 2 and the member 14 is glued at 24 to the lower, inner face of the top member 10.

The bottom members are directed upwardly forming an upwardly directed angular construction, and the hooks 20 and 22 are inserted within the slots 16 and 18 respectively.

The device, when thus constructed, will support a plurality of lollipops 25, 25 when a stick 26 of each is inserted through the two series of holes 14, 14 and 23, 23.

It is to be noted that by upwardly inclining the bottom, the top members 10 and 11 and the bottom members 12 and 13 firmly support the lollipops, which cannot be accomplished by a device in which the bottom is in abutment with the surface upon which the device rests.

While the device is shown as a support for lollipops, it is evident that it can be employed with other commodities capable of insertion through the two series of holes.

I do not limit myself to the particular size, shape, number or arrangement of parts as shown and described as these are given simply as a means for clearly describing my invention.

What I claim is:

1. In a supporting device capable of being formed from a simple blank, in combination, an upwardly directed angular top having a plurality of holes in the angular edge thereof, an upwardly extended angular bottom having a plurality of holes therein in alignment with the top holes and end members carried by the top members locking the top member and the bottom member in fixed position.

2. In a supporting device capable of being formed from a simple blank, in combination, two top members in upwardly directed an-

gular position with respect to each other having a plurality of holes along the angular edge, two bottom members in upwardly directed angular position with respect to each other having a plurality of holes along the angular edge in alignment with the top holes, and end flaps carried by the two top

members locked to each other to hold the top members and the bottom members in fixed position.

10

Signed at New York city in the county of New York and State of New York this 29th day of June, 1926.

MEYER SOYBEL.
